UNITED STATES PATENT OFFICE.

HARRY V. ASHBY, OF ERIE, PENNSYLVANIA.

TOY MOVING-PICTURE MACHINE.

1,206,286.

Specification of Letters Patent. Patented Nov. 28, 1916.

Application filed March 23, 1916. Serial No. 86,139.

To all whom it may concern:

Be it known that I, HARRY V. ASHBY, a citizen of the United States, and resident of Erie, county of Erie, State of Pennsylvania, 5 have invented certain new and useful Improvements in Toy Moving-Picture Machines, of which the following is a specification.

The principal object of my invention is 10 the production of a sturdy toy motion picture machine, which may be manufactured so as to sell for a small amount. To this end the parts of the machine have been arranged and organized in a special manner.

Another feature of my invention resides 15 in the means for fastening the ends of the strip carrying the series of pictures so as to keep the latter in place on the drum.

Still another feature resides in the construction of the drum which comprises two pieces, a single piece forming one head, the cylindrical portion, and the serrated flange.

A further feature consists of the structure 25 and manner of mounting the aperture plate, so that the plate may be adjusted to bring the aperture of the same into register with the pictures carried by the drum.

Still another feature resides in the arrangement and mounting of the aperture 30 plate and lens. These two parts are very simply carried by the support for the drum.

These and other features of the invention, including certain details of construction, will be set forth in the following description and pointed out in the claims.

In the drawings in which like reference characters indicate the same part in the different views, Figure 1 is a front elevation of the machine; Fig. 2 is a side elevation 40 with part of one of the uprights broken away in order to show the star wheel which actuates the drum step by step; Fig. 3 is a sectional view taken on the line 3—3 of Fig. 2; Fig. 4 is a detail sectional view on the line 4—4 of Fig. 1; Fig. 5 is a detail in section showing the means for clamping the ends of the film.

The machine consists of a base 10 having two spaced parallel vertically extending uprights 11. These uprights may be cast integral with the base or may be connected in any other suitable manner. The base with the uprights form a support for the other parts of the machine. At its upper end each 55 upright is formed with a boss 12. As shown,

these bosses are spaced apart and are provided with aligned bores 13. Seated in the bores is a short shaft 14 which carries the drum. This shaft is shorter than the distance between the outside faces of the bosses, 60 so that each end of the shaft is spaced from the outside face of its supporting boss, for a purpose to be described later.

A drum is mounted on the shaft. This drum is made from two pieces of sheet material. One piece forms one head 15, the cylindrical portion 16 and the toothed flange 17. The other piece forms the head 18, and is connected to the cylindrical portion 16 by soldering, or in any other suitable manner. 65 The heads are provided with two central aligned apertures 19 and 20, for mounting the drum on the shaft. A spacing sleeve 21 may be interposed between the heads to keep them properly spaced and prevent 70 them from becoming dished. The cylindrical portion of the drum may be formed with a peripheral bead 22 adjacent the head 15. This bead, together with the tooth flange 17 constitute a means to hold the picture strip 75 23 against lateral displacement on the drum. A leather washer 49 may be inserted between the head 15 of the drum and the adjacent boss in order to keep the drum in position and also to deaden the noise which 80 might result from vibration of the head 15 or other parts.

The cylindrical portion of the drum has a slot 24 extending substantially parallel with the axis of rotation. This slot is designed to have the two ends of the picture strip inserted therethrough, and is of a length and width to permit this. The edges of the slot are rounded off so that the picture strip will not be injured. A rib 25 90 is fastened inside the drum in any suitable manner. This rib is located so that one flat surface of the same is flush with one edge of the slot, so as to afford a support against which the ends of the film may be clamped. 95 The rib is provided with ears 26, on which is pivotally mounted the finger 27. One end of this finger is pressed toward the rib 25 by means of the spring 28. Thus the ends of the picture strip may be inserted through the slot 24 and securely clamped between the finger 27 and the rib 25. This structure provides a simple means for holding the picture strip smoothly against the cylindrical surface of the drum. One of the 100 105 110

heads is provided with an aperture 47 adjacent the clamping means, so that the finger 27 may be manipulated.

Each of the bosses 12 is provided with a 5 transversely extending bore 29. Mounted in each bore is a rod 30, extending radially outside of the drum. The bores are located so that the rods form abutments to hold the shaft 14 in proper position, and so that 10 the rods extend in parallel directions. Set screws 31 in the bosses lock the rods in position.

Slidingly mounted on each rod, and adapted to be locked to the rod by means 15 of a set screw 34 is an arm 33. Each arm has an offset slotted or grooved piece 32, which is arranged to extend parallel to a tangent to the cylinder, and can be adjusted to a position in close proximity to the 20 cylindrical surface of the drum. The offset is necessary in order to clear the toothed flange 17 and locate the grooved piece as close to the drum as possible. The two grooved pieces are parallel to each other, 25 one near each edge of the cylindrical portion of the drum. They may be as long as a plurality of pictures, preferably three. An aperture plate 36 of sheet material is 30 slidingly fitted in the grooves 35 of the grooved pieces. This aperture plate may be of the same length as the grooved pieces. It has a centrally arranged aperture 37, through which the pictures may be viewed. The aperture should be of the same dimensions 35 as a single picture on the picture strip. As the plate is slidingly mounted, it may be adjusted so that the aperture will register with the pictures on the picture strip, when the drum is at rest. If this adjustment were not provided it would be 40 necessary to move the picture strip circumferentially on the drum in order to register the aperture and pictures. Obviously this would be a very tedious process.

45 As previously stated the rods extend outside of the drum. A ring piece 38 having two ears 39 is slidingly mounted on the rods near their ends. Each rod extends through 50 an ear, and is clamped by a set screw 40 carried by each ear. The ring carries a lens 41, through which and the aperture 37 the pictures are viewed. Obviously, the device may be used without the lens. The 55 adjustable mounting of the lens permits it to be positioned to meet the requirements of different observers.

The drum is rotated intermittently by means now to be described. Near the base 60 and below the periphery of the drum, the uprights 11 rotatively carry a shaft 43. This shaft has a star wheel 44 non-rotatively fastened to it, in position to coöperate with the teeth 42 of the toothed flange 17. The 65 design of the star wheel and teeth is such as to give the drum a step by step move-

ment of rotation. That is, the drum alternately has a period of rest and movement. Any other suitable means might be used to give this movement to the drum. The shaft 43 may be rotated by means of a hand crank 47. In order that the drum may be held steady and motionless, between periods of movement, a spring is provided to coöperate with the teeth 42. As shown, the flat portion 48 of this spring is fastened to an upright, below the star wheel. The flat portion has two arms, one on each side of the upright, which extend toward the toothed flange 17, and each arm has a bent end 46 forming a knee, which coöperates 80 with the teeth. When the drum is at a period of rest each knee engages in a space between two teeth, thereby holding the drum steady.

In the operation of the device, a picture 85 strip having a series of motion pictures thereon, of proper length and width, is wrapped around the drum. The ends of the strip are inserted through the slot in the drum, and clamped by the spring pressed 90 finger. The aperture plate is then adjusted so that the aperture registers with the pictures. The lens is adjusted so that the observer can clearly see the pictures, magnified, as by a reading glass. The crank 47 is then turned, causing the picture to successively appear at the aperture of the aperture plate.

Having described the invention what is 100 claimed is:

1. A toy motion picture machine comprising two uprights, a drum rotatably mounted at the upper ends thereof and adapted to carry a series of motion pictures on its cylindrical surface, an aperture plate, means extending from the upper end of the uprights for supporting said plate adjacent the cylindrical surface of said drum, and co-operating means on the drum and uprights 105 for rotating the drum step by step.

2. A toy motion picture machine comprising a support, a drum rotatably mounted on the support and adapted to carry a series of motion pictures on its cylindrical surface, an aperture plate, a rod projecting from said support and arranged radially of the drum and carrying said plate adjacent the cylindrical surface of said drum, and co-operating means on the drum and support for rotating the drum step by step.

3. In a toy motion picture machine, a rotatable drum adapted to carry on its cylindrical surface a strip having a series of motion pictures thereon, a slot in the cylindrical surface, through which the ends of the strip may be thrust, and means located inside of the drum to hold the said ends in position.

4. In a toy motion picture machine, a drum adapted to carry on its cylindrical 130

surface a series of motion pictures, said drum comprising two pieces, a single piece forming one head, the cylindrical surface, and a serrated flange, and a second piece forming the other head.

5. A toy motion picture machine comprising a base, an upright projecting from the base, a drum rotatably supported on the upright, a member carried by the upright and 10 projecting beyond the circumference of the drum, an aperture plate carried by the said member adjacent the cylindrical surface of the drum, a lens spaced from and substantially alined with the aperture in the plate, 15 and means to rotate the drum step by step.

6. In a toy motion picture machine, a drum adapted to carry on its cylindrical surface a series of motion pictures, said drum comprising two pieces, one piece forming a head and the cylindrical surface and the other piece forming the other head, and one of said pieces having a serrated circular flange.

20 7. A toy motion picture machine comprising an aperture plate formed from sheet material, means for supporting and moving a series of motion pictures intermittently

past said aperture plate, means for holding said plate constructed and arranged to allow the plate to be adjusted longitudinally of 30 the series of pictures and means for adjustably supporting said holding means whereby the plate may be adjusted toward and from the series of pictures.

8. A toy motion picture machine comprising a rotatably mounted drum, means for rotating the drum intermittently, two parallel bars arranged on opposite sides of the drum and carrying an aperture plate adjacent the surface of the drum and a lens 40 adapted to coöperate with the aperture plate in viewing pictures carried by the drum.

9. A toy motion picture machine comprising a support, a drum rotatably mounted thereon and formed with a projecting circular bead at one end of its cylindrical surface and flange means arranged at the other end, an aperture plate supported adjacent said surface and means for rotating the drum 45 step by step.

In testimony whereof I affix my signature.

HARRY V. ASHBY.
